UNITED STATES PATENT OFFICE.

ALMON W. COBLEY AND BAYARD D. KUNKLE, OF WILKINSBURG, PENNSYLVANIA,
ASSIGNORS TO WESTINGHOUSE ELECTRIC AND MANUFACTURING COMPANY, A
CORPORATION OF PENNSYLVANIA.

ELECTRICAL SYSTEM.

1,175,344.

Specification of Letters Patent. Patented Mar. 14, 1916.

Application filed December 18, 1914. Serial No. 877,949.

To all whom it may concern:

Be it known that we, ALMON W. COBLEY and BAYARD D. KUNKLE, citizens of the United States, and residents of Wilkinsburg, in the county of Allegheny and State of Pennsylvania, have invented a new and useful Improvement in Electrical Systems, of which the following is a specification.

Our invention relates to electrical systems for automobiles and particularly to controlling devices therefor.

Our invention has for its object to provide a simple and efficient means for controlling an electric system whereby the several circuits of said system may be controlled in their proper sequence by a unitary mechanism.

Our invention is particularly adapted for use in connection with starting and ignition mechanisms for internal combustion engines. The ignition circuit is controlled simultaneously with the circuit of the starting motor and it is, therefore, impossible to manipulate the ignition switch to produce a premature spark while the circuit of the starting motor is closed and the engine shaft is being rotated by the motor.

Another feature of our invention resides in the fact that it may be employed for controlling the circuits of dynamo-electric machines that operate either as motors to start engines or may be driven by the engines as generators to furnish current for lighting and ignition purposes and charging storage batteries. A dynamo-electric machine of this type may be permanently connected to the engine shaft at a fixed speed ratio and provided with series and shunt field windings for operation either as a series or a compound motor and as a compound generator.

When employed in connection with a dynamo-electric machine of the type above described, the controlling mechanism operates to disconnect the shunt field winding from the battery before the armature and the series field windings are disconnected therefrom and before the ignition circuit is rendered inoperative. This arrangement prevents the energizing of the shunt field winding when the other circuits are broken and the ignition circuit is inoperative.

The details of our invention will be described in connection with the accompanying drawings in which—

Figure 1 is a view, in front elevation, of a switching mechanism constructed in accordance with our invention, the cover plate being removed. Fig. 2 is a view, in longitudinal section, of the mechanism of Fig. 1. Fig. 3 is a view, in longitudinal section, taken at right angles to the view of Fig. 2, of the mechanism of Fig. 1. Fig. 4 is a diagrammatic view of circuits and apparatus embodying our invention.

Referring particularly to Figs. 1, 2 and 3, a switch 1 comprises a substantially cylindrical flanged casing member 2, the ends of which are inclosed respectively by a disk 3 of insulating material and a cover plate 4 of metal or other suitable material. A stationary contact member 5, which is connected to a terminal member 6, coacts with a movable contact member 7 that is carried by a blade spring 8. The contact member 7 is connected to a terminal member 9 by a shunt conductor 10.

The relative position of the contact members 5 and 7 is controlled by a hollow cylinder 11 of insulating material which is rotatably mounted upon a short shaft 12. The cylinder 11 is provided with a flat portion 13 which, in one position of the cylinder, registers with the spring 8 to permit the separation of the contact members. The cylinder 11 constitutes, in effect, a cam which controls the movable contact member 7 in accordance with its position.

A conducting plate 14, comprises three projections or contact fingers 15, 16 and 17 which coact with a series of stationary contact members 18, 19, 20 and 21. The cylinder 11 is actuated by means of a handle or lever 22 which may be fixed thereto or made removable, as desired.

Reference may now be had to Fig. 4 which is a diagrammatic view of circuits and apparatus embodying our invention. A dynamo-electric machine, the armature of which is indicated at 23, is provided with series field windings 24 and a shunt field winding 25. The circuit comprising the series field windings 24 and the armature of the dynamo-electric machine is controlled by

the contact members 5 and 7. The shunt field winding 25, which is connected to an intermediate or third brush 26, is connected to the contact member 21.

- 5 An ignition circuit, which is supplied either from the battery or from the dynamo-electric machine 23, as the case may be, comprises an interrupter 27, an induction coil 28, distributor 29, and the usual engine 70 spark plugs 30. A magneto ignition circuit, which may be employed if a dual ignition system is desired, comprises a magneto generator 31, an induction coil 32, a distributor 33, and engine spark plugs 34.
- 10 When the switch is in its "off" position, as illustrated, the flat portion 13 of the cylinder 11 registers with the spring 8, and the armature circuit of the dynamo-electric machine is broken at the contact members 15 and 7. The contact fingers 15 and 17 respectively engage the contact members 18 and 19 to ground the terminals of the magneto 31 and thereby render the circuit supplied by it inoperative. The battery ignition circuit is rendered inoperative because the circuit of the primary windings of the induction coil 28 is broken at the contact member 20. The circuit of the shunt field windings 25 is broken at the contact member 21.

15 To start the engine, the lever 22 is actuated to the right, as viewed in Fig. 1, until the contact fingers 15 and 17 respectively engage contact members 19 and 21. When the contact finger 17 engages the contact member 20, the cam operation of the cylinder 11 has effected engagement of the contact members 5 and 7 to close the armature circuit of the dynamo-electric machine, and 20 the ignition circuit is rendered operative by the connection of the contact member 20 to the contact member 19, which is grounded.

25 The further actuation of the lever 22 to effect the engagement of the contact members 17 and 21 has the additional effect of connecting the contact member 21 to the contact member 19, the other circuits being maintained as just described. The dynamo-electric machine 23 then operates as a compound wound motor, the series field windings 24 and the shunt field winding 25 assisting each other to establish a strong magnetic field and thereby produce a correspondingly heavy torque.

30 When the engine starts under its own power, the dynamo-electric machine 23 will be driven by the engine at the same speed ratio to operate as a compound wound generator. The shunt field winding, which is 55 the main exciting winding, is then opposed by the series field windings 24 because the current traversing the latter windings is reversed during generator operation. The dynamo-electric machine operates as a self-regulating generator by reason of the fact

that the voltage between the terminals of the shunt field winding 25 is varied in accordance with the current traversing the armature circuit. This effect is produced by the shifting of the magnetic field caused by 70 armature reaction and which is proportional to the armature current, as is well known.

When the battery becomes fully charged, the lever 22 may be actuated to its mid-position to disconnect the shunt field winding 75 25. The dynamo-electric machine then operates as a series motor, but at the ordinary speeds of the engine, little or no current will be received by the dynamo-electric machine because of its comparatively high counter 80 electromotive force. In this position of the switch, the dynamo-electric machine would operate automatically as a motor to propel the car in case the engine should become stalled.

85 To stop the engine, it is only necessary to bring the lever 22 to its "off" position to open the circuits of the respective field windings and to render the ignition circuit inoperative. It will be understood that both the battery and the magneto ignition circuits will be rendered inoperative in the "off" position of the switch because the circuit of the primary winding of the induction coil of the battery ignition circuit is broken at 90 the contact member 20 and the terminals of the magneto generator 31 are grounded.

95 The advantages of our invention are that a unitary mechanism may be employed to control the circuits of a motor dynamo and the ignition mechanism employed in connection with an internal combustion engine. The several circuits are opened and closed in their proper sequence, and the switch may be adjusted to produce any desired relation 105 of the several circuits.

Many changes may occur to those skilled in the art to which our invention appertains, and such modifications may be made without departing from the spirit of our invention as fall within the scope of the appended claims.

110 We claim as our invention:

1. In an electrical system, the combination with an internal combustion engine, a dynamo-electric machine operatively connected thereto, said dynamo-electric machine having a series field winding, an ignition circuit, and a battery, of means for simultaneously connecting said field winding to said battery and rendering said ignition circuit operative.

115 2. In an electrical system, the combination with an internal combustion engine, a dynamo-electric machine having series and shunt field windings, an ignition circuit, and a battery, of means for simultaneously connecting said series field winding to the battery and rendering said ignition operative and for connecting said shunt field winding 120 125 130

in circuit with said battery while maintaining the connections of said series field winding and said ignition circuit.

3. In an electrical system, the combination with an internal combustion engine, a dynamo-electric machine operatively connected thereto, said dynamo-electric machine having a shunt field-magnet winding, an ignition circuit, and a battery, of a switching mechanism having successive positions for simultaneously controlling the armature circuit of said dynamo-electric machine and said ignition circuit and for controlling the circuit of the shunt field-magnet winding.
- 15 4. In an electrical system, the combination with an internal combustion engine, a dynamo-electric machine operatively connected thereto, said dynamo-electric machine having series and shunt field-magnet windings, a battery, and an ignition circuit, of a switching mechanism having progressive positions in one of which the field windings are disconnected from the battery and the ignition circuit is inoperative, a second position in which one of the field windings is connected in circuit and the ignition circuit is operative, and a third position in which both field windings are in circuit with the battery and the ignition circuit is operative.
- 25 5. In an electrical system, the combination with an internal combustion engine, a dynamo-electric machine operatively connect-

ed thereto, an ignition circuit for said engine, and a battery, of a plurality of sets of relatively movable contact members for controlling the circuits of said dynamo-electric machine and said ignition circuit, and means for actuating one movable contact member through a plurality of progressive positions while another movable contact member is actuated through a lesser number of positions.

6. In an electrical system, the combination with a dynamo-electric machine having series and shunt field windings, an ignition circuit, and a source of current, of a unitary switching mechanism having progressive positions in one of which the field windings are disconnected from the battery and the ignition circuit is inoperative, a second position in which the series field winding is connected to the battery and the ignition circuit is operative, and a third position in which the series and shunt field windings are connected to the battery and the ignition circuit is operative.

In testimony whereof, we have hereunto subscribed our names this 16th day of Dec., 1914.
